UNITED STATES PATENT OFFICE.

LINCOLN TIJOU, OF CORPUS CHRISTI, TEXAS.

SANITARY SOAP-DISH.

1,194,096.

Specification of Letters Patent. Patented Aug. 8, 1916.

Application filed January 24, 1914. Serial No. 814,069.

To all whom it may concern:

Be it known that I, LINCOLN TIJOU, a citizen of the United States, and resident of Corpus Christi, Nueces county, Texas, have, 5 invented certain new and useful Improvements in Sanitary Soap-Dishes, of which the following is a specification containing a full, clear, and exact description, reference being had to the accompanying drawings, forming 10 a part hereof.

My invention relates to improvements in sanitary soap dishes, and the object of my invention is to construct a novel means wherein soap may be kept dry after using.

15 A further and more specific object of my invention is to provide an improved receptacle comprising a drain cup and a brush wherein the brush is designed for use in cleansing hands, or scrubbing or the like and 20 which brush when not in use is arranged to support upon its bristles or flexible abrading surfaces a piece of soap so that the soap is kept in a dry condition and the brush itself is drained in order to preserve the brush.

25 With the above purposes in view my invention consists in certain novel features of construction and arrangement of parts as will be hereinafter more fully described, pointed out in the claim and illustrated by 30 the accompanying drawings, in which—

Figure 1 shows in plan a device constructed according to my invention, the piece of soap therein; Fig. 2 is an elevation of the device as shown in Fig. 1; and Fig. 3 is a 35 longitudinal sectional elevation showing the device as in use.

Referring by numerals to the accompanying drawings: 5 designates a receptacle, constructed in such manner and of such material 40 as to retain water. The inner face of the wall of the receptacle is provided with a ledge 6 which constitutes a support for a brush 7.

The brush back is provided with a series 45 of perforations 8 and the face of the back of the brush from which the bristles project declines toward the center of the brush, and the bristles 9 are arranged in tufts of uni-

form lengths which present a surface lowest at its central portion and highest at its ends 50 so that, when a cake of soap such as shown at 10 is placed upon the bristles of the brush the soap is in contact with the brush only at its ends, thereby offering circulation of air about the entire cake of soap so as to permit 55 it to dry rapidly after using.

It is to be particularly observed that the brush is supported above the bottom of the receptacle so that there is room beneath the brush to contain the water drained from the 60 soap as well as the brush. It is to be observed further that, when the brush is in place in the receptacle, its upper face inclines toward the center, so that the brush back is drained and will automatically dry 65 itself. It is to be observed further that the soap is supported only at its ends so that air may circulate about practically the entire cake of soap.

While I have shown and described the 70 brush as a bristle brush, I do not wish to be understood as limiting myself to this construction, as hemp, hair or rubber bristles or teeth may be employed without departing from the spirit of my invention. 75

I claim:

An improved holder for a cake of soap, comprising a back having (when inverted) a draining-surface which inclines downwardly from its ends toward its center, said back 80 having a number of drain-perforations formed vertically therein for draining the liquid from said inclined surface at various points; and tufts of brush-material, all of uniform length, projecting from said inclined surface, to form a receptacle for a cake of soap, above the said downwardly and centrally inclined surface. 85

In testimony whereof, I have signed my name to this specification, in presence of two 90 subscribing witnesses.

LINCOLN TIJOU.

Witnesses:

THOMAS B. SOUTHGATE,
FRANK RABB.
